UNITED STATES PATENT OFFICE.

RUDOLPH H. JULIEN, OF COPAS, MINNESOTA.

NEST.

Application filed April 10, 1923. Serial No. 631,152.

To all whom it may concern:

Be it known that I, RUDOLPH H. JULIEN, a citizen of the United States, residing at Copas, in the county of Washington and 5 State of Minnesota, have invented certain new and useful Improvements in Nests, of which the following is a specification.

This invention relates to poultry nests and the primary object is to provide means 10 whereby hens of proper weight may be automatically separated from the hens which are under weight so that the poultry owner may be enabled to dispose of the hens which are not up to the standard requirements and 15 retain the more valuable fowls and avoid the expense of feeding and raising the non-productive or less profitable fowls. The invention seeks to provide a mechanism which will be operated by the fowls and will act 20 in such a manner that properly developed fowls will be caused to leave the nest at a different point from the entrance while the light weight fowls will be prevented from so leaving the nest and will be forced to 25 leave at the same point where they entered. The invention also provides a device which may be used as a trap nest when so desired. Other objects of the invention will incidentally appear in the course of the following 30 description, and the invention resides in certain novel features which will be particularly pointed out in the appended claims.

One embodiment of the invention is illustrated in the accompanying drawings, in 35 which—

Figure 1 is a perspective view of my improved nest viewed from the exit end thereof and showing the said end open;

Fig. 2 is a horizontal section with parts 40 broken away, and

Fig. 3 is a central vertical longitudinal section.

In carrying out the invention, I employ a housing 1 which may be of any desired form 45 and dimensions and is shown as of a generally oblong formation having an arched top and provided with a substantial floor 2. The ends of the housing are open, and doors 3 and 4 are arranged to close the entrance and 50 exit ends respectively. The door 4 controlling the exit end of the housing is mounted at or adjacent its lower end upon a hinge rod 5 for swinging movement toward and from the end of the housing and is provided centrally at its lower edge with a vertical notch 6, the purpose of which will presently ap-

pear. The door 3 controlling the entrance end of the housing is also mounted upon a hinge rod 7 similar to the hinge rod 5 but disposed above the lower edge of the door, 60 as clearly shown in Fig. 3, so that, when this door is in its lowered position shown in Fig. 2 and in full lines in Fig. 3, the nest-supporting frame 8 will be supported in an elevated position and the portion of the door 65 below the hinge rod will be arranged to act as a lever in effecting the closing movement of the door. This door 3 is provided in its upper portion with a longitudinally extending slot 9, and a weight 10 is mounted on 70 the door and adjustable along the said slot so that the door may be set to close under the influence of any predetermined weight acting upon its inner or lower end. A graduated scale 11 may be provided upon the 75 inner side of the door along the said slot 9, as shown in Fig. 2, and by setting the weight 10 at any one of the graduations, the door will be adjusted so that it will not close unless a fowl weighing at least as much as 80 the amount indicated by the graduation at which the weight is secured should enter the nest. The nest 12 may be of any desired construction and rests upon the nest-supporting frame 8 within the housing and between the 85 doors, and the parts should be so proportioned that the weight of the upper portion of the door 3 will balance the weight of the lower portion of the door, the nest and the nest frame. The nest-carrying frame 8 is 90 pivotally connected with the lower edge of the door 3 and has a slidable connection with the hinge rod 5 carrying the door 4, as shown, and it may be of any desired or preferred form but is illustrated as consisting 95 of a stout wire or light rod doubled upon itself to present a substantially V-shaped frame having eyes 13 at one end to engage in openings 14 provided therefor in the lower edge of the door 3 and provided at its 100 apex or opposite end with a slotted tongue 15 slidably engaging the hinge rod 5 and playing through the notch or slot 6 in the door 4. A lever or link 16 is disposed at the outer side of the housing 1 and has one end 105 pivotally attached to the door 4 and its opposite end pivotally attached to the door 3, as clearly shown. Upon the top of the housing 1 at the exit end thereof is provided a spring latch 17 which may be engaged over 110 the upper edge of the door 4 when it is desired to utilize the device as a trap nest, and

this latch is normally held in inoperative position by a wedge or similar device 18 inserted between the top of the housing and the latch, as shown in Figs. 1 and 3 and as 5 will be readily understood.

It is thought the operation of the nest will be readily understood. The weight 10 is shown in the accompanying drawings as secured to the door 3 at the point indicated 10 by the numeral 3 upon the scale of graduations 11. When thus set, if a hen weighing three pounds or more should enter the housing, when she enters the nest 12 her weight will depress the nest and the frame 8 causing 15 the same to swing downwardly about the hinge rod 5 and at the same time slide inwardly inasmuch as the downward movement of the nest will cause the lower end of the door 3 to swing downwardly and 20 outwardly about the hinge rod 7 so that the door will swing up to the closed position indicated by the dotted lines in Fig. 3. The movement of the door 3 will be transmitted through the link 16 to the door 4 so that 25 said door will be swung downwardly to the position shown in Fig. 1 and in dotted lines in Fig. 3, and the hen will consequently be prevented from leaving the housing through the same end at which she entered and will 30 pass out over the door 4 as is obvious. When the hen leaves the nest, she will at once step upon the door 4 and her weight will continue to act to hold the door 3 in its raised closed position, but as soon as 35 the door 4 is relieved of the weight of the hen, the door 3 will swing downwardly inasmuch as the weight of said door combined with the weight 10 will overbalance the door 4 and the parts will be restored to the 40 initial position shown in full lines in Fig. 3. Should a hen weighing less than three pounds enter the housing and step upon the nest, her weight will be insufficient to close the door 3 and, therefore, the door 4 will 45 remain closed and the fowl will be obliged to leave by the same opening through which she entered and will return to the flock of underweight fowls. It will be understood that the nest is to be located in a partition 50 between two runways or pens and eventually all the light weight fowls will be separated from those of standard weight without any attention on the part of the owner, and the underweight fowls may then be sold while 55 the good layers may be retained for the eggs. If it be desired to operate the nest as a trap nest, the link 16 is released from the entrance-controlling door 3 and the wedge 18 withdrawn so that the latch 17 60 will engage the exit-controlling door 4 and prevent downward movement of the same. Then when a hen enters the nest, her weight will operate the door 3 so as to close the same and both doors will remain closed until 65 the owner or caretaker opens the door 3

so as to release the hen. He will then be enabled to make any examination which may be desired, or mark or treat the hen in case necessity should require the administration of medicine or disinfectants, or any other operation incident to the care of poultry should be needed. 70

My device is exceedingly simple in its construction and compact in the arrangement of its several elements. It operates 75 automatically and with certainty so that no attention on the part of the owner is needed in order to keep it in operative condition. The nest 12 rests loosely upon the frame 8 and may be removed when cleaning of the 80 nest is necessary by merely sliding it out over said frame and either door. The doors, the nest and the housing may conveniently be made from sheet metal so that they may be produced at a low cost and will be strong 85 and durable.

Having thus described the invention, what is claimed as new is:

1. The combination of a housing having open ends, doors mounted for swinging 90 movement near the bottom of the housing to close the respective ends thereof, a nest mounted within the housing and connected directly with the door controlling the entrance end thereof whereby a predetermined 95 weight imposed upon the nest will close said door, and a connection between the upper portions of the doors whereby the door controlling the exit end will be opened as the door controlling the entrance end is closed. 100

2. The combination of a housing having open ends, doors controlling said ends and mounted to swing downwardly from the respective ends, the door controlling the entrance end of the housing being hingedly 105 mounted at a point above its lower edge, a nest mounted within the housing and having pivotal connection with the lower edge of said door, and a connection between the upper portions of the doors whereby when the 110 door controlling the entrance end of the housing is closed the other door will be opened.

3. The combination of a housing having open ends, a door controlling the entrance 115 end of the housing and pivotally supported at a point near but above its lower edge, a door controlling the exit end of the housing and pivotally mounted at its lower edge, a nest-supporting frame having pivotal engagement at one end with the lower edge of the entrance-controlling door and having 120 slidable engagement at its opposite end with the pivot of the exit-controlling door, and a nest resting on said frame. 125

4. The combination of a housing having open ends, a door controlling the entrance end of the housing and pivotally mounted at a point above its lower edge, a door controlling the exit end of the housing and 130

pivottally mounted at its lower edge and provided at said edge with a longitudinally extending slot, a link connecting said doors, above the pivots thereof, a nest-supporting frame having pivotal connection at one end with the lower edge of the entrance controlling door and provided at its opposite

end with a slotted tongue slidably engaging the pivot of the exit controlling door and playing through the slot in said door, and a nest resting on said frame.

5 In testimony whereof I affix my signature.

RUDOLPH H. JULIEN. [L. S.]
